(57) **CLAIM**

The ornamental design for a stirring utensil, as shown and described.

DESCRIPTION

FIG. 1 is a perspective view showing a first side, first edge and front-tip end of our stirring utensil;

FIG. 2 is a perspective view showing a second side, second edge and back handle end of our stirring utensil;

FIG. 3 is an elevation view of the first side of the stirring utensil shown in FIG. 1;

FIG. 4 is a plan view of the first edge of the stirring utensil shown in FIG. 1 with the first side being on top and the second side being on the bottom;

FIG. 5 is a magnified plan view of a joint section of the first edge of the stirring utensil shown in FIG. 4;

FIG. 6 is a magnified plan view of the back handle end of the first edge of the stirring utensil shown in FIG. 4;

FIG. 7 is a magnified plan view of the front-tip section of the first edge of the stirring utensil shown in FIG. 4;

FIG. 8 is an elevation view of the second side of the stirring utensil shown in FIG. 1;

FIG. 9 is a plan view of the second edge of the stirring utensil shown in FIG. 1 with the first side being on top and the second side being on the bottom;

FIG. 10 is a magnified plan view of a joint section of the second edge of the stirring utensil shown in FIG. 9;

FIG. 11 is a back handle end plan view of the stirring utensil shown in FIG. 1;

FIG. 12 is a magnified back handle end plan view of the stirring utensil shown in FIG. 11;

FIG. 13 is a front tip end plan view of the stirring utensil shown in FIG. 1; and

FIG. 14 is a front tip end magnified plan view of the stirring utensil shown in FIG. 13.

FIG. 15 is a perspective view showing a first side, first edge and front-tip end of a second embodiment of our stirring utensil;

FIG. 16 is a perspective view showing a second side, second edge and back handle end of our stirring utensil illustrated in FIG. 15;

FIG. 17 is an elevation view of the first side of the stirring utensil shown in FIG. 15;

FIG. 18 is a plan view of the first edge of the stirring utensil shown in FIG. 15 with the first side being on top and the second side being on the bottom;

FIG. 19 is a magnified plan view of a joint section of the first edge of the stirring utensil shown in FIG. 18;

FIG. 20 is a magnified plan view of the back handle end of the first edge of the stirring utensil shown in FIG. 18;

FIG. 21 is a magnified plan view of the front-tip section of the first edge of the stirring utensil shown in FIG. 18;

FIG. 22 is an elevation view of the second side of the stirring utensil shown in FIG. 15;

FIG. 23 is a plan view of the second edge of the stirring utensil shown in FIG. 15 with the first side being on top and the second side being on the bottom;

FIG. 24 is a magnified plan view of a joint section of the second edge of the stirring utensil shown in FIG. 23;

FIG. 25 is a back handle end plan view of the stirring utensil shown in FIG. 15;

FIG. 26 is a magnified back handle end plan view of the stirring utensil shown in FIG. 25;

FIG. 27 is a front tip end plan view of the stirring utensil shown in FIG. 15; and

FIG. 28 is a front tip end magnified plan view of the stirring utensil shown in FIG. 27.

The views shown magnified are shown this way for clarity of illustration.
